UNITED STATES PATENT OFFICE.

JOHN FEHRENBATCH, OF CINCINNATI, OHIO.

APPARATUS FOR CONTROLLING THE FLOW OF STEAM.

No. 833,313.

Specification of Letters Patent.

Patented Oct. 16, 1906.

Application filed January 6, 1905. Serial No. 239,898.

To all whom it may concern:

Be it known that I, JOHN FEHRENBATCH, a citizen of the United States, residing at Cincinnati, in the county of Hamilton and State of Ohio, have invented certain new and useful Improvements in Apparatus for Controlling the Flow of Steam, of which the following is a specification.

My invention relates to devices for controlling the flow of steam through apparatuses employing steam as the heating agent.

One of the objects of my invention is to control the temperature produced by steam heat in a chamber or coil of pipes within certain required limits not exceeding the initial temperature of steam employed in such a manner that both the receiving and discharge valves may be turned wide open without affecting the temperature within the chamber or coil of pipe and without increasing the flow of steam to or from the chamber or coil of pipes beyond that previously provided for doing the work required.

Another object of my invention is to economize in the use of steam and prevent its waste in doing certain work by proportioning the area of the inlet and outlet orifices, or either of them, so as to restrict the use of steam in a chamber or coil of pipes to the amount necessary for doing the work required, regardless of how wide open the receiving or discharge valves may be.

The features of my invention are fully set forth in the description of the accompanying drawings, forming a part of the specification, in which—

Figure 1 is a central vertical section of the preferred form of steam-controller. Fig. 2 is a section on line xx , Fig. 1. Fig. 3 is a modification of the construction in Fig. 1. Fig. 4 is a central longitudinal section of a steam-chamber with my improved controllers. Fig. 5 is an enlarged central vertical section of the preferred form of apparatus.

For convenience of illustration of one of the simplest forms of my improvement I have represented in Fig. 4 a sterilizing-chamber which is adapted to be heated for sterilizing articles by the direct application of steam to the same and affixed to which are the controllers for regulating the temperature by controlling the flow of steam to or from the chambers to the amount necessary for doing the work.

55 A represents an ordinary cylinder.

B B represent the heads of the cylinder.

C represents the sterilizing-chamber in which the articles are to be placed and subjected to the direct heat of the steam.

D represents the controller in the inlet-pipe D'. This controller is shown in an enlarged view, Fig. 1.

In the preferred form of construction the inlet-pipe section D² is offset from the opposite end of the pipe D³.

E represents the controller, seated in the body of the steam-pipe.

a represents the maximum passage-way of the controller.

b represents a regulating-screw.

c represents the lateral passages intersecting passage a. A single passage may be employed provided the area of cross-section of such passages or passage will equal the area of cross-section of the main or central passage a.

The size or area of the orifices of the lateral passages c is regulated by the regulating-screw b. In order that this regulation may be readily made and the device properly adjusted to do the required work, I have provided a screw-plug F directly above the screw b, so that the plug can be readily taken out and the screw adjusted, and the plug can be replaced, and the controller will be constant in its adjustment and not subjected to the control of attendants, as that of ordinary valves. I have found by experience that the ordinary valves cannot be adjusted so as to properly control the flow of steam for producing required temperature for doing work. Besides they are subjected to constant manipulation, and consequently extravagant use of steam far beyond the amount necessary for doing the work required.

d represents the controller in the outlet passage-way G from the chamber C.

Requirements of the controller.—Controllers must be constructed or adjusted with reference to the initial pressure of the steam to be employed, the square feet of heating-surface, and the desired temperature in the chamber or coil of pipes in which the work required of the steam is to be performed, and a controller should be placed in both the outlet and inlet of such chamber or coil of pipes. The method of regulating the required work of the steam will be understood by the following example: Where a certain temperature is required not exceeding that due to the

initial or boiler pressure by the direct application of the steam heat it will be sufficient for practical purposes if the area of the orifice of the outlet-controller be approximately 5 .00196 of one square inch for each square foot of the inner surface of the chamber of an apparatus such as a sterilizer, for example. Then let .00196 equal a constant. Let twenty 10 square feet equal interior surface of the chamber. Then we have $.00196 \times 20 = .0392$ of a square inch—area required for orifice of outlet-controller.

Then to determine the area required for orifice of inlet-controller multiply the area of 15 orifice of outlet-controller by the pressure in pounds per square inch of steam representing the temperature desired and divide the product by the initial or boiler pressure, and the quotient will give the required area of orifice 20 of the inlet-controller.

Example: Let .0392 equal area of orifice 25 of outlet-controller. Let forty-five pounds equal pressure per square inch required in the chamber. Let ninety pounds equal initial or boiler pressure per square inch. Then we have $\frac{.0392 \times 45}{90} = .0196$ of a square inch—area required for orifice of the inlet-controller.

In case of an apparatus employing a chamber 30 for the admission of steam for boiling, with a low pressure, water contained in the chamber surrounding the steam-chamber, as in an apparatus for boiling surgical instruments, it will be sufficient for practical purposes and to prevent the accumulation of 35 condensation in the chamber resulting from the steam in doing its work if the area of the orifice of the outlet-controller contains .01 of a square inch for each square foot of the 40 heating-surface covered with the water to be boiled.

In ordinary boiling by the use of steam in cooking or boiling kettles where a higher temperature is required in the steam-chamber than in the case of boiling surgical instruments it will be sufficient for practical purposes and to prevent the accumulation of condensation resulting from the steam in doing its work if the area of the orifice of the 45 outlet-controller contains .003 of one square inch for each square foot of heating-surface to be covered by water or other fluid. If desired, a by-pass valve, as shown in Fig. 3, 50 may be connected with the inlet-pipe to provide for heating the water or other fluid rapidly, and when heated to the boiling-point the by-pass should be closed and the operation left to the inlet-controller and the outlet-controller to do the work. The same 55 may be done for the same purpose in any apparatus, such as sterilizers or apparatus for boiling surgical instruments and for all other purposes for which the controller may be used. If it be desired to use an inlet-controller 60 in cases like this, the area may be de-

termined by multiplying the area of the outlet-controller by any desired pressure representing the temperature required in the steam-chamber, not exceeding the initial or boiler pressure, and dividing the product by 70 the boiler-pressure, and the quotient will give the required area of the orifice of the inlet-controller.

The foregoing stated dimensions given are approximately correct, for controllers without the regulating device and are sufficient for all practical purposes where absolute accuracy and very close regulations are not required; but for absolute accuracy and to secure the greatest possible economy in the use 80 of steam for the purposes herein set forth the controllers with regulating device are preferred, and for the purpose of providing greater latitude between the minimum and maximum temperature that may be obtained from any given initial or boiler pressure the areas of orifices of outlet and inlet controllers, as specified for controllers without the regulating device, should be increased twenty-five per cent.

In the outlet-orifice of the cylinder shown in Fig. 4 the orifice is pierced through a plug set in the pipe and is not provided with a regulating device, and therefore cannot be adjusted to suit any conditions except those 95 for which the area of its orifice was specially made. The advantage, therefore, of the regulating device is plainly apparent.

The construction of the controller in its preferred form is shown in Figs. 1 and 3 with 100 means provided for readily adjusting the size of the orifice.

In the modified form shown in Fig. 3 I have shown a by-pass valve H, which taps into the pipe below the controller-orifice a. 105 This by-pass valve will be found useful in case of necessity for relieving the outlet-controller of undue condensation of steam or of water which may have accumulated in the pipes while the machine or apparatus was 110 not in use.

At the commencement of operations it will also be found advantageous as a by-pass valve for the inlet-controller to hasten the heating of the chamber or coils of pipe or 115 hasten the boiling of the water or other fluid, as above stated.

In ordinary cooking-kettles where it is not desired to regulate the temperature of the vessel to any predetermined degree, but is 120 simply desired to economize the use of steam, the outlet-controller alone will accomplish this in a very practical manner by proportioning the area of said outlet-orifice to the square feet of heating-surface which is to be 125 employed, such proportioning being preferably .003 of a square inch to each square foot of the heating-surface.

The advantages of having an inlet or outlet controller which may be easily regulated 130

to quite a large range of conditions possesses very many advantages over the unadjustable form.

The form shown in Fig. 1 is the preferred form for ordinary conditions, and the advantages are as follows: First, it is made of a pipe-section with threaded connections at each end, so that when coupled up in the system it may be readily adjusted to any desired condition by unscrewing the plug F and adjusting the adjusting screw-bolt b; second, the controller pipe-section may be made in quantities of any given size and dimension and can be readily applied by simply adjusting the plug which controls the area of orifice, so that it is easily fitted to the desired condition; third, in case the orifice should become clogged or obstructed the parts are very easily cleaned without uncoupling the pipe. Again, the pipe-section containing the adjusting-plug and offset plug F may be carried in stock without requiring to make a special plug or controller for each condition that arises.

Having described my invention, I claim—

1. In an apparatus employing a heating-chamber, means for securing and maintaining a predetermined temperature, consisting of a controller-plug, having a predetermined restricted orifice inclosed in the steam-inlet pipe in front of the heating-chamber, and a controller, having a predetermined orifice inclosed within the outlet-pipe from the chamber, said orifices being proportioned to each other and to the area of the heating-surface and the initial pressure of steam, substantially as described.

2. In an apparatus of the class described employing a steam-inlet and a steam-outlet pipe, a controller having a restricted orifice located in the outlet-pipe, a controller located in the inlet-pipe having an orifice, and means for regulating the area of said orifice, whereby a predetermined temperature may be obtained with a minimum amount of steam used in the apparatus by regulating the area of the orifice proportionately to the area of the outlet-orifice, the area of heating-surface and the initial pressure, substantially as described.

3. A steam-chamber of given dimensions provided with an inlet-controller and an outlet-controller, having respective orifices of predetermined sizes proportioned relative to one another and to the said chamber and initial pressure, whereby a given temperature may be maintained in said chamber, substantially as described. 55

4. In an apparatus of the class described, an inlet-controller for regulating the flow of steam through said apparatus, having an offset section, a removable plug threaded into said offset, a controller-plug located in the pipe opposite said removable plug, provided with a main orifice and an orifice intersecting said main orifice, a regulating-plug adapted to be projected across said intersecting orifice for regulating the area thereof, and a by-pass passage independent of said controller, having a valve-stem passing through the wall of the pipe-section, substantially as described. 60 65 70

5. In an apparatus of the class described, means for introducing and circulating steam through said apparatus, means for controlling the amount of steam utilized in said heating apparatus, consisting of a controller located within the outlet-pipe system, a restricted orifice through said controller, the area of said orifice being proportioned to the steam-pressure admitted to said apparatus and to 75 the area in square feet of the surface to be heated, substantially as described. 80

6. In a device of the class described, the heating-chamber, a steam inlet and outlet therefor, a controller-plug seated in the outlet-pipe and formed with a restricted steam-escape orifice, having a predetermined proportion in area relative to the area of the heating-surface of said vessel and to the pressure admitted to said heating-chamber, 85 90 whereby a maximum amount of heat is utilized with a minimum amount of steam, substantially as described.

In testimony whereof I have hereunto set my hand.

JOHN FEHRENBATCH.
